CLAIM

The ornamental design for a portable BBQ charcoal grill, as shown and described.

DESCRIPTION

FIG. 1 is a perspective view of a portable BBQ charcoal grill showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an exploded view with the clasps removed for clarity of showing the disclosure.

The portions of the portable BBQ charcoal grill shown in broken lines form no part of the claimed design.

1 Claim, 8 Drawing Sheets
